STRAP JOINT-FORMING MECHANISM

William C. Childress, Oak Park, and Arvid I. Ericsson, Chicago, Ill., assignors to Signode Steel Strapping Company, Chicago, Ill., a corporation of Delaware

Application June 15, 1950, Serial No. 168,196

7 Claims. (Cl. 81—9.1)

1

Our invention relates to strap joint-forming mechanism, or as it is rather generally termed, sealing mechanism. The mechanism is especially adapted for producing joints between overlapping portions of flat or ribbon like metallic strapping, which is usually subject to considerable tension, and a joint-reinforcing sleevelike seal. Such strapping is employed in a variety of ways in many fields, such for example, as in the form of tensioned encircling loops for the binding and reinforcement of boxes, packages and bundles, and of aggregates or groups of such objects, containing or consisting of a wide diversity of merchandise.

One well known and extensively used joint for this purpose is produced by shearing, inwardly from their edges, the adjacent or juxtaposed longitudinal margins of overlapping strap portions and the sleevelike seal to form pairs of slits that extend a short distance inwardly from the margins and define tongues in both the overlapping portions and the encompassing seal, each tongue, defined by a pair of such slits, being displaced or offset laterally out of the normal plane of strap and seal to cause edges of strapping and seal at opposite sides of slits to lie in planes that intersect. Thus, adjacent layers of strapping and seal on opposite sides of a slit are caused to abut each other with abrupt opposing edge-to-edge interlocking shoulders which resist relative longitudinal movement of the overlapping portions of strapping and create an effective tension-resistant joint.

The most feasible if not the necessary production of such joints requires mechanism which, upon a single operation and essentially simultaneously will produce both complete or true marginal slits through both the seal and the strapping and also the necessary offsetting of the tongue formed and defined by the slits to insure that adjacent sheared edges of both strapping and sleeve on opposite sides of the slits lie in crossing planes so as to form the edge-to-edge abutting shoulders. If both of the overlapping strap portions and both layers of the sleeve are not sheared or cut entirely through the offsetting will merely bend the metal and only curved rather than edge-to-edge shoulders and metal joints will result. Heretofore, however, in order to insure that both the seal and strapping are actually cut or sheared through, rather than merely bent, and sufficiently offset to provide interlocking of requisite effectiveness, the mechanism for producing joints of this type have necessarily left the tongues protruding inwardly to-

2

ward the thing or things being bound by the strapping so far beyond the plane of the body of the joint as to cause such joints to be subject to some objection. For example, the tongues have projected sufficiently to raise the joint and cause it to interfere with the sliding of boxes or bundles upon or against each other and to catch obstructions, such as the joints or the strapping of other boxes or bundles. This may subject joints to sudden strains caused by shock in transit or in handling with liability of rupture. And the tongues have protruded sufficiently far to indent and mar the underlying surfaces or edges of superposed bundles or the constituents of bundles. This last phenomenon is particularly objectionable where the bound bundles are of relatively delicate or easily dented and marred material such, for example, as sheets of tin plate and sheets of thin steel currently used in automobile bodies and fenders.

The principal object of our invention is to provide a joint forming or sealing mechanism that will produce joints of the sheared and offset tongue type which are as strong as those heretofore produced but wherein the tongues do not protrude to such an objectionable extent.

Another object is to provide a simple and effective tool or machine for producing joints comparable in strength to those heretofore known but wherein the projection of the offset tongue is reduced.

A further object is to provide a method for producing such joints.

Our invention will be illustrated and explained as embodied in a hand operated sealing tool although, as will be readily appreciated, the mode of operation and the essential mechanism can be performed by and incorporated in power operated machines.

Other objects and advantages will hereinafter appear.

In general our tool or joint forming machine includes jaws which compress the sleeve or seal tightly about the overlapping portions of the ribbonlike metallic strapping, then shear and offset marginal tongues in both the strapping and seal, sufficiently to insure edge-to-edge crossing engagement between layers of seal and strapping, and finally retract or pull back the tongues to reduce the amount they protrude from the finished joint, without, however, detracting from the strength and effectiveness of the joint.

A typical embodiment of our invention is incorporated in a simple hand operated sealing tool

is illustrated in the accompanying drawings wherein:

- Fig. 1 is a side elevation of such a tool;
- Fig. 2 is a top plan thereof;
- Fig. 3 is a front elevation;
- Fig. 4 is an enlarged side elevation of the head of the tool with one side plate removed to expose the seal folding jaw and the slitting and offsetting mechanism in open position preparatory to being applied to the work;

Fig. 5 is a similar view except that the folding jaw has been in part removed, illustrating the relation of the folding jaws and the slitting and offsetting mechanism at the completion of the slitting and offsetting operation;

Fig. 6 is a view similar to Fig. 5, showing the relation of the folding jaws and the slitting and offsetting mechanism at the completion of a joint forming operation, when the tongues of the joint have been retracted;

Fig. 7 is an enlarged view of merely the tips or active portions of the folding jaws and the slitting and offsetting mechanism in the three positions shown, for the entire tool, in Figs. 4, 5 and 6; and

Fig. 8 is a perspective of one edge of a joint showing how the marginal edges of the sleeve-like seal and the overlapping strap portions are sheared and the intervening tongue is offset to insure the necessary crossing edge-to-edge shoulder abutment and then the tongue is retracted to reduce its protraction.

Referring first to Figs. 1, 2 and 3, the specific hand operable tool illustrated includes a head 10 and a pair of handles 11 and 12. The inner end of handle 12 is located between and assists in the spacing of a pair of head side plates 13 and 14 and is rigidly attached thereto by a pair of bolts 15. Handle 11 is pivotally mounted between side plates 13 and 14 on a pivot bolt 16. Head side plates 13 and 14 are further retained in proper spaced relation by a pair of jaw pivot pins 17 and a pair of movement-directing and stop pins 18. All four of these pins are of reduced diameter where they project into side plates 13 and 14 so as to provide side-plate spacing shoulders 19 and 20, as shown most clearly in Fig. 3; and the entire head assembly is clamped together by the bolts 15 and 16 and their respective nuts 21.

Pivottally connected to jaw pivots 17 between the side plates are a pair of complementary seal-folding jaws 25, each of which has three laterally spaced inwardly pointing hooklike tips 26, 27 and 28. The three tips of one jaw confront corresponding tips of the other jaw and each has an inwardly opening depression or recess 29 which lies opposite a like opening or recess in the corresponding tip of the other jaw. The connection between each folding jaw 25 and its pivot pin 17 is made with a tight bearing fit so that each jaw may oscillate about its pivot pin without other relative movement between jaw and pin.

The rear ends and confronting inner faces of folding jaws 25 are provided with a pair of parallel slots 35 and 36 in which, as will be later explained, notching and offsetting blades 39 slidably and pivotally fit. By means of a toggle pin 41 the rear of each folding jaw 25 is connected to one end of a link 42, the other ends of the two links being connected to a guiding and notching blade actuating pin 46. Pin 46 is connected to handle 11 by means of a pair of links 47 and a pin 48. The opposite ends of pin 46

are flattened to form a pair of keys 49, each key fitting into a slot or keyway 50—51 formed in the inner face of side plates 13 and 14, respectively, midway between and perpendicular to a line intersecting the axes of the two pivot pins 17. Thus it will be understood that as handle 11 is moved between a position such as indicated in Fig. 4 to a position such as indicated in Fig. 6, the toggle connection formed by pin 43, links 47, pin 46, links 42 and pins 41 will swing the folding jaws 25 from open position to closed position and the flattened key ends of guide pin 46 will travel from near the top of guides 50—51 toward the bottom thereof; and that thereafter reverse movement of handle 11 will return the folding jaws from closed to open position.

Each of the previously mentioned notching and offsetting blades 39 has a hole 60 through which the corresponding jaw pivot pin 17 loosely passes, and near the rear upper end each blade is provided with an outwardly opening recess or slot 61 which slidably accommodates a block 62 that has a bearing fit upon the corresponding pin 41. Also each blade 39 has on its upper outer edge an angular cam surface 63 which bears against and rides along the corresponding guide pin 18. And further each blade 39 has along its inner upper edge a rounded cam surface 65 and along its longitudinal inner edge two merging angularly related surfaces 66—67. Of these, the surface 66 may be considered as an extension of the cam surface 65. A pair of rollers 70 are carried with a bearing fit upon centering pin 46, each roller lying between and in a plane of two opposing notching and offsetting blades and in a position to engage cam surfaces 65—66—67 of both blades.

Each notching and offsetting blade 39 is in the form of a flat parallel sided plate which fits in its proper slots 35—36 of the folding jaws 25 and each, somewhat like the folding jaws, has an inwardly pointed hooklike tip 71. This tip of each blade 39 has an angularly related surface 72, which constitutes two spaced shearing edges, one at each side of the blade, and a sloping or beveled tongue offsetting shoulder therebetween. Beyond each surface 72 and separated therefrom by a small recess 73 each notching blade tip 71 is formed with a tongue retracting horn 77.

A chair or anvil 75 lies between the folding jaws 15 and the notching and offsetting blades 39, being slotted to accommodate the notching blades, and is retained in place by trunnions 76 which project into holes in the side plates 13 and 14.

In operation handle 11 is swung to separate it from handle 12 to open the tool for application to the work. In this condition, as shown in Fig. 4, the tips of both sealing jaws 25 and the tips of the notching and offsetting blades 39 are fully separated and the notching blades are retracted. If the joint between the overlapping strap portions 80 and 81 is to be reinforced by a sleeve 82 of the flange type, the jaws and the notching and offsetting blades are now open sufficiently to enable the tool to be applied with the chair or anvil 75 against the sleeve back plate 82(a) and the sleeve flanges 82(b) flanked by the jaws and notching blades as shown in Fig. 4 with the shearing edges and offsetting shoulders of each notching blade separated some distance from the lateral outer corners of the reinforcing sleeve 82 as shown in Fig. 4 and as indicated by the full lines 72 of Fig. 7. Now, with the tool applied to the

work, the handle is swung from the open position shown in Fig. 4, through the intermediate position shown in Fig. 5 to the final position shown in Fig. 6.

During the initial stages of the movement of handle 11 from tool open to closed position the linkage 47—46—42 between the handle 11 and folding jaws 25 causes the rear ends of jaws 25 to be separated and the hooklike tips 26 to approach, as previously explained; and the movement of rollers 70 between and over the rounded cam surfaces 65 cause the tips 71 of the notching and offsetting blades 39 to approach each other. These initial approaching movements of the folding jaws 25 and of the notching and offsetting blades 39 bends the sleeve flanges 82(b) inwardly and rearwardly to cause the sleeve to encircle the overlapping strap portions 80—81 and to clamp the strap portions and encircling sleeve tightly back against anvil 75. As soon as the rollers 70 enter upon the straight portions 66 of the cam track, these portions then being parallel, further outward movement of the top ends of the blades is not forced and in fact is inhibited by the pins 18. The notching and offsetting blades are therefore pushed straight downwardly by the blocks 62 acting in the slots 61 inasmuch as the blocks have a considerable downward component of movement, they being well beyond the pivot pins 17 at this point in their travel. Also the angle made by the slots 61 with the vertical can be such as to give just the desired degree of relative movement between the jaws and blades. At the end of travel of the handles in the closing direction therefore the strapping is tightly wrapped in the seal, the notches are formed, and the tongues are well offset downwardly.

As the handles are pulled apart the jaws immediately start their retracting movement by swinging outwardly. During the early portion of the return travel of the handles the notching blades are pulled approximately straight upwardly since rocking movement is prevented by the rollers 70 between the relatively parallel cam surfaces 66. The lower edges of the tongues are therefore caught by the inwardly directed tongue retracting horns 77. These horns therefore pull the tongues straight backwardly until the rollers 70 emerge from the approximately parallel portions 66 of the cam surfaces of the blades on to the sharply outwardly flaring portions 65. When the flared portions 65 of the cam surfaces are reached, the notching and offsetting blades are permitted to pivot inwardly at the top and this movement is forced by the block 62 being brought against the ends of the slots 61. This rocks the retracting horns 77 outwardly until they clear the edges of the tongues. With slight additional opening movement of the handles the tool can be removed from the joint.

From the above description of one embodiment of our invention, it will be seen that the seal is automatically tightly wrapped about the strapping, a pair of tongues on each side of the strapping and seal are sheared and offset a considerable distance below the plane of the strapping so as to insure good angularly opposed sheared surfaces, and that thereafter with opening movement of the tool, the tongues are retracted a considerable distance so as to project only slightly below the plane of the strapping. The effect is to produce a thinner and smoother joint than can safely be made if it is attempted simply to offset the tongues the desired amount directly because of the danger of insufficient shearing action taking place with this small degree of

offset. Furthermore, all of this is accomplished by the operator in a natural manner so that an operator need not be taught any different technique when first introduced to the use of this novel sealing tool.

Having described our invention, what we claim as new and useful and desire to secure by Letters Patent of the United States is:

1. A tool for producing a joint between overlapping portions of metallic strapping and an encircling metallic reinforcing sleeve, comprising a pair of spaced side plates, a pair of pivot pins held by and bridging between said side plates, a pair of folding jaws, each jaw being pivotally mounted on one of said pivot pins, said jaws having confronting hooklike tips which approach each other to clamp the strap portions and sleeve when said jaws are oppositely rocked about said pins, a pair of shearing and offsetting blades, each blade being loosely mounted on one of said pins by means of an opening therein substantially larger than said pin so that said blade and the jaw mounted on said same pin may move longitudinally relative to each other, an operating linkage pivotally connected to said jaws for rocking said jaws about said pivot pins, means including cam surfaces on said blades and a member engageable therewith carried on said linkage to rock said blades about said pivot pins, and means holding said side plates in place.

2. A tool for producing a joint between overlapping portions of metallic strapping and an encircling metallic reinforcing sleeve, comprising a pair of spaced side plates, a pair of pivot pins held by and bridging between said side plates, a pair of folding jaws, each jaw being pivotally mounted on one of said pivot pins, said jaws being adapted to clamp the strap portions and sleeve when oppositely rocked about said pins, a pair of notching and offsetting blades, each blade having an opening therein substantially larger than said pin through which said pin projects to mount the blade thereon and so that said blade and the jaw mounted on said same pin may have limited movement relative to each other, said blades having confronting hooklike tips for grasping the edge of the strap portions encircled by the sleeve when said blades are rocked toward each other, a movable operating linkage pivotally connected to said jaws for rocking said jaws about said pivot pins, a blade engaging means on said linkage and cooperating means on said blades adapted to be engaged by said blade engaging means to rock said blades about said pivot pins to bring said blades into notching and offsetting position, and a lost motion connection between said linkage and said blades to move said blades longitudinally relative to said jaws and to rock said blades from notching and offsetting position, whereby when said linkage is moved in a first direction said blades and jaws are rocked together to grasp the strap edges encircled by the sleeve and subsequently said blades are moved primarily longitudinally relative to said jaws while said jaws hold the strap and sleeve to notch the strap and sleeve and to offset portions thereof a predetermined distance, and when said linkage is moved in the opposite direction said blades are retracted primarily longitudinally to return the offset portions a part of the offset distance, and subsequently said jaws and said blades are rocked away from each other to release the strap and sleeve, and means holding said side plates in place.

3. A tool for producing a joint between over-

lapping portions of metallic strapping and an encircling metallic reinforcing sleeve, comprising a pair of spaced side plates, a pair of pivot pins held by and bridging between said side plates, a pair of folding jaws, each jaw being pivotally mounted on one of said pivot pins, said jaws being adapted to clamp the strap portions and sleeve when oppositely rocked about said pins, a pair of notching and offsetting blades, each blade being loosely mounted on one of said pins by means of an opening therein substantially larger than said pin so that said blade and the jaw mounted on said same pin may move longitudinally relative to each other, said blades having confronting hook-like tips for grasping the edge of the strap portions encircled by the sleeve when said blades are rocked toward each other, a movable operating linkage pivotally connected to said jaws for rocking said jaws about said pivot pins and connected to said blades for moving said blades longitudinally and about said pivot pins, cam means on said blades and a cooperating member on said linkage and movable therewith to rock said blades about said pivot pins, whereby when said linkage is moved in a first direction said blades and jaws are rocked together to grasp the strap edges encircled by the sleeve and subsequently said blades are moved primarily longitudinally relative to said jaws while said jaws hold the strap sleeve to notch the strap and sleeve and to offset portions thereof a predetermined distance, and when said linkage is moved in the opposite direction said blades are retracted primarily longitudinally to return the offset portions a part of the offset distance, and subsequently said jaws and said blades are rocked away from each other to release the strap and sleeve, and means holding said side plates in place.

4. A tool for producing a joint between overlapping portions of metallic strapping and an encircling metallic reinforcing sleeve, comprising a pair of spaced side plates, a pair of pivot pins held by and bridging between said side plates, a pair of folding jaws, each jaw being pivotally mounted on one of said pivot pins, said jaws being adapted to clamp the strap portions and sleeve when oppositely rocked about said pins, a pair of notching and offsetting blades, each blade being loosely mounted on one of said pins by means of an opening therein substantially larger than said pin so that said blade and the jaw mounted on said same pin may move longitudinally relative to each other, means held by said side plates for limiting pivotal movement of said blades so that said blades are then constrained for longitudinal movement, said blades having confronting hooklike tips for grasping the edge of the strap portions encircled by the sleeve when said blades are rocked toward each other, a movable operating linkage pivotally connected to said jaws for rocking said jaws about said pivot pins and pivotally and slidably connected to said blades for moving said blades longitudinally and about said pivot pins, cam means on said blades and a cooperating member on said linkage and movable therewith to rock said blades about said pivot pins, whereby when said linkage is moved in a first direction said blades and jaws are rocked together to grasp the strap edges encircled by the sleeve and subsequently said blades are moved primarily longitudinally relative to said jaws while said jaws hold the strap sleeve to notch the strap and sleeve and to offset portions thereof a predetermined distance, and when said linkage is moved in the opposite direction said blades are retracted primarily longitudinally to

return the offset portions a part of the offset distance, and subsequently said jaws and said blades are rocked away from each other to release the strap and sleeve, and means holding said side plates in place.

5. A tool for producing a joint between overlapping portions of metallic strapping and an encircling metallic reinforcing sleeve, comprising a pair of spaced side plates, a pair of pivot pins held by and bridging between said side plates, a pair of folding jaws, each jaw being pivotally mounted on one of said pivot pins, said jaws being adapted to clamp the strap portions and sleeve when oppositely rocked about said pins, a pair of notching and offsetting blades, each blade being loosely mounted on one of said pins by means of an opening therein substantially larger than said pin so that said blade and the jaw mounted on said same pin may move longitudinally relative to each other, first cam means on said blades, a pair of pins held by said side plates and engageable with said cam means for guiding said blades in pivotal and longitudinal movements, said blades having confronting hooklike tips for grasping the edge of the strap portions encircled by the sleeve when said blades are rocked toward each other, a movable operating linkage pivotally connected to said jaws for rocking said jaws about said pivot pins and pivotally and slidably connected to said blades for moving said blades longitudinally and about said pivot pins, second cam means on said blades and a cooperating member on said linkage and movable therewith to rock said blades about said pivot pins, whereby when said linkage is moved in a first direction said blades and jaws are rocked together to grasp the strap edges encircled by the sleeve and subsequently said blades are moved primarily longitudinally relative to said jaws while said jaws hold the strap sleeve to notch the strap and sleeve and to offset portions thereof a predetermined distance, and when said linkage is moved in the opposite direction said blades are retracted primarily longitudinally to return the offset portions a part of the offset distance, and subsequently said jaws and said blades are rocked away from each other to release the strap and sleeve, and means holding said side plates in place.

6. In a tool for producing a joint between overlapping portions of metallic strapping and an encircling metallic reinforcing sleeve, having a pair of spaced side plates, a pair of pivot pins held by and bridging between said side plates, a pair of folding jaws, each jaw being pivotally mounted on one of said pivot pins, said jaws having confronting hook-like tips which approach each other to clamp the strap portions and sleeve when said jaws are oppositely rocked about said pins, an operating linkage pivotally connected to said jaws for rocking said jaws about said pivot pins, and means holding said side plates in place, the improvement which comprises a pair of shearing and offsetting blades, each blade being loosely mounted on one of said pins by means of an opening therein substantially larger than said pin so that said blade and said jaw mounted on said same pin may move relative to each other, a blade actuating means on said linkage means, and cam means on said blades adapted to be engaged by said blade actuating means as said linkage means is operated to pivot said blades to bring them into shearing and offsetting position, stop means limiting such pivotal movement of said blades, and means connecting said linkage mechanism to said blades to move said blades long-

gitudinally relative to said jaws to shear and offset the overlapping strapping portions and encircling sleeve.

7. In a tool for producing a joint between overlapping portions of metallic strapping and an encircling metallic reinforcing sleeve, having a pair of spaced side plates, a pair of pivot pins held by and bridging between said side plates, a pair of folding jaws, each jaw being pivotally mounted on one of said pivot pins, said jaws having confronting hook-like tips which approach each other to clamp the strap portions and sleeve when said jaws are oppositely rocked about said pins, an operating linkage pivotally connected to said jaws for rocking said jaws about said pivot pins, and means holding said side plates in place, the improvement which comprises a pair of shearing and offsetting blades, each blade being loosely mounted on one of said pins by means of an opening therein substantially larger than said pin so that said blade and said jaw mounted on said same pin may move relative to each other, a blade actuating means on said linkage means, cooperat-

ing means on said blade adapted to be engaged by said blade actuating means as said linkage means is operated to move said blades to bring them into shearing and offsetting position, and a lost motion connection between said blades and said linkage mechanism to move said blades longitudinally relative to said jaws to shear and offset the overlapping strapping portions and encircling sleeve.
